UNITED STATES PATENT OFFICE.

FRANK M. GARMAN, OF ALMA CENTER, WISCONSIN.

FURNACE REGULATOR.

Application filed February 14, 1922. Serial No. 536,460.

To all whom it may concern:

Be it known that I, FRANK M. GARMAN, a citizen of the United States, residing at Alma Center, in the county of Jackson and State of Wisconsin, have invented a new and useful Furnace Regulator, of which the following is a specification.

This invention has reference to stoves and furnaces, and more particularly to the damper construction thereof.

The primary object of the invention is to provide means for automatically controlling the dampers of the stove or furnace to insure an even heat.

Another object of the invention is to provide a damper operating means controlled by the expansion and contraction of the furnace wall, the operating means including an electrically controlled motor.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

The figure illustrates an elevational view of a furnace disclosing a controlling device constructed in accordance with the present invention, as applied.

Referring to the drawing in detail, the reference character 5 designates a furnace which may be of any desired construction, the same being provided with a door 6 hinged from the upper edge thereof, the door being provided to control the passage of air to the firebox of the furnace.

A damper 7 is in the pipe 8 and controls the passage of air through the pipe to increase or decrease the draught through the furnace.

A supporting bar 9 is secured to the undersurface of the floor beams 10, directly over the furnace 5, which supporting bar is designed to accommodate the brackets 11 that support the pulleys 12, the pulleys being arranged at opposite ends of the bar 9.

A depending bracket 13 is bolted to the supporting bar 9, and to which bracket is pivotally connected the arm 14 which has one end connected with the bar 15 which carries a switch element 16 on the outer

end thereof. Pivotally connected to the bar 15 is a vertical rod 17 which has its lower end extended through a suitable opening in the furnace casing, where the rod contacts with the furnace proper 18, the rod 17 being sensitive to movements of the furnace wall 18, due to expansion and contraction of the furnace wall.

A flexible member 19 connects the door 6 and damper 7, the flexible member being shown as moving over the pulleys 11, so that when the damper 7 is open, the door 6 is closed, or vice versa. Associated with the flexible member 19, is an electric motor 20 which has an arm 21 that is connected with the flexible member 19, so that when the arm 21 is moved, the flexible member 19 is also moved to accomplish the purpose of the invention.

Switch members 22 are associated with the switch element 16, whereby the circuit to the motor 20 will be completed, when the switch element 16 contacts with one of the switch members 22. The arms 14 and 15 are pivotally connected at 23 and the arm 14 is pivotally connected to the bracket 13 at 13'. In order that the point of connection between the arms 14 and 15, may be moved with respect to the rod 17, a chain 24 is provided which has connection with the outer end of the arm 14, and passes over the drum 25. Thus it will be seen that upon moving the drum 25 to wind the chain 24 thereon, the point of connection 23 may be moved to cause the switch members to be operated under comparatively low degree of temperature. A weight indicated at 15' is secured to the arm 15 at a point adjacent to the outer end thereof, so that as the wall 18 moves downwardly, the weight together with the weight of the rod 17 will cause the arm 15 to move downwardly.

The device is shown in the drawing as in its neutral or inactive position.

Assuming that the temperature in the furnace rises, the expansion of the furnace wall 18 will move the rod 17 upwardly causing the switch element at the outer end of the arm 15 to engage the uppermost switch member 22 and contact 22' with the result that the circuit to the motor is completed to cause the motor to operate in one direction or in a manner to cause the arm 22 to move downwardly opening the damper 7 to cool the furnace.

When the furnace cools, it is obvious that

the rod 17 will drop causing the arm 15 to be moved and complete a circuit to the motor by its contact with the lowermost switch element 22, and contact 22' with the result that arm 21 is moved upwardly opening the door 6 and closing the damper 7.

By an operation of the drum 25, the arm 14 may be moved with respect to the rod 17 and arm 15 to cause the arm 15 to operate at predetermined temperatures.

When the furnace becomes heated and the wall 18 moves upwardly under the heat of the furnace, the outer end of arm 15 will move downwardly to engage the contact member 22 completing the circuit to the motor which circuit supplies electric energy to the motor in a manner to cause the motor to operate in the opposite direction to the end that the door 6 will be moved to its closed position and the damper 7 opened to cool the furnace.

Having thus described the invention, what is claimed as new is:

A draft regulating device for a furnace having a damper and a hinged ash pit door,

including a supporting bar, a bracket depending from the supporting bar, an arm having pivotal connection with the bracket at a point adjacent to one end of the arm, a bar carrying a switch element at its free end, pivotally connected to the arm at a point adjacent to the bracket, a rod connected with the bar at a point adjacent to its connection with the arm, said rod having its free end resting on the furnace wall, a motor having an arm, a flexible member connecting the motor arm, damper and ash pit door, contact members in circuit with the motor to cause the motor to move in opposite directions, to move the motor arm and damper and ash pit door, and said bar adapted to move to bring the switch element carried thereby into engagement with the contact members to control the movements of the motor.

In testimony that I claim the foregoing as my own, I have hereto affixed my signature.

FRANK M. GARMAN.
